UNITED STATES PATENT OFFICE.

CARL V. JOHNSON, OF GOLDFIELD, NEVADA, ASSIGNOR TO INDISPENSABLE MANUFACTURING CO., OF GOLDFIELD, NEVADA.

WINDING DEVICE FOR DROP-LIGHTS.

1,254,698.

Specification of Letters Patent. Patented Jan. 29, 1918.

Application filed April 9, 1915, Serial No. 20,216. Renewed August 8, 1917. Serial No. 135,188.

To all whom it may concern:

Be it known that I, CARL V. JOHNSON, a citizen of the United States, and a resident of Goldfield, in the county of Esmeralda and State of Nevada, have invented a new and Improved Winding Device for Drop-Lights, of which the following is a full, clear, and exact description.

This invention relates to combined chandeliers and drop-lights, and the general objects of the invention are to provide a comparatively simple, inexpensive, durable and attractive device of the character referred to which embodies a winding mechanism arranged in the body of the chandelier, whereby a light suspended from the chandelier may be adjusted to any desired position.

More specific objects of the invention are the provision of simple, effective and improved means for adjusting the tension of the winding spring; of maintaining the brushes in firm contact with the collector rings; for connecting the frame of the device with the chandelier body so that ready attachment and detachment can be effected; for yieldingly retarding the rotation of the winding wheel; for stopping the winding wheel when the drop-light is in the proper position and releasing the wheel to permit the cord to wind; for preventing a strain to be exerted on the conductors of the cord where such conductors are connected with the winding wheel; for guiding the movement of the cord out of the chandelier, and for centering the device in the chandelier.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention, and wherein similar characters of reference indicate corresponding parts in all the views,

Figure 1 is a fragmentary sectional view of a chandelier with the winding mechanism for the drop-light cord mounted therein;

Fig. 2 is a transverse section of the winding mechanism;

Fig. 3 is a side view of the winding mechanism;

Fig. 4 is a horizontal section of the lower part of the frame of the device; and

Fig. 5 is a side view with parts in section, of the combined chandelier and drop-light.

In the present instance the drop-light is shown in connection with a chandelier, but it is to be understood that certain features of the invention are not limited to this combination. The chandelier comprises a casing or body A having upper and lower sections 1 and 2 that form the housing for the winding mechanism of the drop-light, and around the casing is an annular flange or ring 3 which carries a plurality of electric lights B, the chandelier including suspension chains 4 that are suspended from a ceiling support C. The drop-light D includes a lamp and a flexible conductor cord 5' which extends out of the bottom of the lower section 2 of the casing from a winding device within the casing, whereby the lamp 5 can be raised or lowered to any desired point to suit the preference of the user.

The various parts of the winding mechanism are carried by a frame E which, in the present instance, is made of strips of metal formed into top and bottom sections 6 and 7 and side sections 8 and 9, the sections being fastened together by screws or equivalent fasteners 10, whereby a skeleton structure 85 is provided. The top section 6 has side extensions 10' which overlap the side sections 8 and 9, and these ear-forming extremities 10' are vertically disposed and overlapped with ears 11 soldered or otherwise fastened to the bottom section 2 of the casing A, the ears 11 being vertically slotted, and passing through the slots are screws 12 which screw into the ears 11, the arrangement being such that by loosening the screws 12 slightly the lower section 2 of the casing can be detached. The top of the frame E is provided with an arched plate 13, and a vertical bolt 14 has its lower end screwed into this plate so that the bolt serves to clamp the upper section 100 1 of the casing in place.

Within the frame E and journaled in bearing openings 15 in the side sections 8 and 9 of the frame is a horizontal shaft 16 which carries the centrally disposed winding wheel 17. Surrounding the shaft and fastened thereto by a set-screw 18 or equivalent means is a sleeve of insulation 19, and on this sleeve are clamped metal collector rings 20 and 21 at opposite sides of the wheel 17. Cooperating with these collector rings are metal or other brushes 20^a and 21^a, respectively, which

are carried by holders 22. These holders have their upper ends pivotally connected by bolts or equivalent means 23 with the opposite sides of the arched portion 24 of the 5 section 6 of the frame, whereby the brushes are free to move on an axis parallel with the shaft 16. Helical springs 25 are connected with the holders 22 and with some fixed part of the frame, such as the top plate 10 13, as shown in Fig. 2, and these springs exert a pull in a direction to maintain the brushes firmly against the collector rings. The brushes 20^a and 21^a are connected in circuit by wires 20^b and 21^b.

15 The wheel 17 comprises a pair of disks 26 faced on both sides with pieces of insulation 27, and the edges of the disks are bent oppositely so as to form a flaring periphery for guiding the cord 5' and preventing wear 20 thereof during winding and unwinding. The two plates or disks of the wheel are fastened to a hub ring 28 by a screw 29. The lamp cord 5' is made up of a pair of conductors 30 and 31 which pass out of openings 25 in the disks of the wheel and are connected respectively with the collector rings 20 and 21. One of these openings 32 is shown in Fig. 2, the other opening being directly behind it, and the extremities of the 30 conductors are fastened by screws 33 with the collector rings. The conductor cord is of flat cross-section, as shown in Fig. 1, and it is of such width as to freely enter between the side disks of the wheel, and the convolutions 35 of the conductor will all lie in a single plane, whereby there is no danger of the cord conductor binding and interfering with the proper operation. To prevent a strain from being exerted on the terminals of the 40 conductors where they are fastened by the screws 33 to the collector rings, a strain device is provided. This device in the present instance is shown as a flexible element 34 which passes through openings 35 in the 45 disks of the wheel, the element being formed into a knot or enlargement 36 at one end to prevent it from being drawn through the adjacent opening 35; and a knot 37 is formed at the opposite side of the wheel, and the 50 ends 38 of the flexible element or tape 34 are engaged under a spring clip or finger 39 extending radially of the wheel and fastened by a screw 40 to the collector ring 20. This strain-taking device 34 is, as shown in Fig. 55 2, about one hundred and twenty degrees displaced from the openings 32 out of which the conductors pass from the wheel to the collector rings, and thus when the cord conductor is fully unwound the strain is taken entirely by the device 34, and there is no danger of the conductors being pulled out of electrical connection with the collector rings.

The winding of the cord on the wheel is 60 effected by a spiral spring 45 which has its inner end 46 fastened to the shaft 16, and its

outer end 47 fastened to a drum 48 which is loose on the shaft 16. This drum has in its periphery teeth 49 adapted to engage with spring pawls 50 carried by flanges 51 on a disk 52, this disk being disposed adjacent the drum 48 and having its flanges 51 fastened to the side section 9 of the supporting frame E. By turning the drum 48 in an anti-clockwise direction, Fig. 3, the spring 45 can be adjusted to the proper tension, whereby the drop-light will be fully raised by the spring. This spring is so arranged that when the wheel 17 turns during the unwinding of the conductor cord, the spring will be tightened to thereby raise the drop-light when the wheel is released.

A stop catch is employed for preventing the wheel 17 from turning and winding the conductor cord when the drop-light has been lowered to the desired position. The catch 85 is in the form of a lever 53 fulcrumed at 54 on one side of the lower section 7 of the frame E, and this lever is formed with a lug 55 that is adapted to engage in any recess 56 formed between teeth 57 in the periphery 90 of one of the wheel disks. This lever has attached to opposite extremities pull chains 58 and 59, respectively, whereby the catch or lever can be rocked to engage or disengage the winding wheel. A helical extension 95 spring 59' has its upper extremity connected with upwardly-extending arms 60 on the catch or lever and its lower end is anchored at 61 on a suitable part of the frame E. The spring is adapted to occupy a position with 100 its axis disposed to one side or the other of a dead center line passing through the pivot or fulcrum 54 and the anchored lower end of the spring at the point 61, whereby the catch will be held by the spring in either locking 105 or unlocking position. By pulling downwardly on the chain 58 the catch is released so that the wheel will turn and wind up the cord. By pulling on the chain 59 the catch is thrown into engagement with the wheel 110 and enters the nearest recess 56. To retard the rotation of the winding wheel spring brake elements 62 and 63 are employed, these being formed of a strip of spring metal clamped between the top of the frame E and 115 the top plate 13, with the extremities of the strip bearing against the periphery of that flange or disk of the wheel other than the disk having the recesses 56, as shown in Fig. 3. The wheel has spaced recesses 64 in its 120 periphery in which the spring brakes are adapted to engage and thereby assist in retarding the movement of the wheel. The tension of the spring brakes may be adjusted by screws 65 arranged in the extremities of the areuate top piece 13, and the inner ends of these screws are adapted to engage with the spring brakes to bow the same more or less and thereby vary the tension.

To insure the centering of the mechanism in 130

the casing of the chandelier the bottom of the frame E has a circular horizontal plate 66 fastened to the bottom thereof, and this plate engages in the approximately hemispherical bottom part of the casing section 2, as shown in Fig. 1. This centering plate 66 has an opening 67 through which the cord conductor 5' extends, and the cord conductor is guided by a pulley 68 journaled in the lower part of the frame E in such position that the pulley is tangential to a vertical line passing through the axis of the winding wheel, as clearly shown in Fig. 2.

The pull chains 58 and 59 are fastened to the catch or lever 53 by means of the said lever having its upper edge provided with a vertical recess 69, and a link 70 of the chain is inserted in the recess and retained therein by a U-shaped wire or staple 71 which is passed horizontally through the catch, and the ends 72 of the staple are bent backwardly, as clearly shown in Fig. 4. The chain is of that type consisting of hollow spherical links 73 connected by the straight double-headed links 71.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters

Patent:

1. A chandelier including a body, a drop-light winding mechanism in the body and including a supporting frame, said body being made in sections, ears on one of the sections, and fastening means for securing the ears to the said frame.

2. A chandelier including a body, a drop-light winding mechanism in the body and including a supporting frame, said body being made in sections, ears on one of the sections, fastening means for securing the ears to the said frame, and a centering element carried by the frame and adapted to internally engage the section of the body having the said ears.

3. A chandelier comprising a body having a removable lower section, a drop-light winding mechanism mounted in the body and including a supporting frame, oppositely disposed upwardly extending ears on the said removable section of the body, said ears

being slotted, and fasteners on the frame engaging in the slots of the ears for detachably securing the said removable section to the frame.

4. In a drop-light, the combination of a wheel, a conductor cord fastened to and adapted to wind on the wheel, a catch in the form of a lever having means adapted to engage the wheel to prevent rotation thereof, and a helical extension spring having one end connected with the lever and the other end anchored at a point whereby the spring will occupy either of two positions with its axis to one side of a dead center line passing through the fulcrum of the lever and the anchored end of the spring, whereby the catch is held in either locking or unlocking position.

5. In a drop-light, the combination of a winding wheel, a conductor cord adapted to wind on the wheel, a catch for holding the wheel against winding, a pull chain, and a connection between the pull chain and catch, said connection being formed by a recess in the catch for receiving a link of the chain, and a keeper in the form of a staple attached to the catch and extending across the recess to retain the chain therein.

6. In a drop-light, the combination of a supporting frame, a shaft journaled therein, a wheel fastened to the shaft, a conductor cord connected with the wheel and adapted to wind thereon, a coiled spring having one end connected with the shaft, a drum to which the outer end of the spring is connected, teeth on the said drum, and pawls fixed with respect to the said frame and adapted to engage the teeth for permitting the drum to be turned in a direction to wind and tension the spring.

7. In a drop-light, the combination of a spring-turned wheel, a conductor cord adapted to wind on the wheel and consisting of two conductors, collector rings connected with the wheel, said wheel having openings through which the conductors extend to the respective collector rings to which the conductors are connected, and a strain device mounted on the wheel and engaging the conductor cord to prevent strains being exerted on the conductors where they are connected with the collector rings, said strain device consisting of a member extending through the wheel from one side to the other and engaging over the conductor cord.

In testimony whereof I have signed my name to this specification in the presence of two subscribing witnesses.

CARL V. JOHNSON.
